(57) **CLAIM**

The ornamental design for an electronic cigarette as shown and described.

DESCRIPTION

FIG. 1 is a bottom, front, left perspective view of an electronic cigarette according to our design;

FIG. 2 is a top, rear, right perspective view of the electronic cigarette of FIG. 1;

FIG. 3 is a top elevational view of the electronic cigarette of FIG. 1;

FIG. 4 is a bottom elevational view of the electronic cigarette of FIG. 1;

FIG. 5 is a right elevational view of the electronic cigarette of FIG. 1;

FIG. 6 is a left elevational view of the electronic cigarette of FIG. 1;

FIG. 7 is a front elevational view of the electronic cigarette of FIG. 1; and,

FIG. 8 is a rear elevational view of the electronic cigarette of FIG. 1.

1 Claim, 7 Drawing Sheets
